(57) **CLAIM**

The ornamental design for a post assembly for a mobile workstation, as shown and described.

DESCRIPTION

FIG. 1 is a front, top, right side perspective view of a post assembly for a mobile workstation showing our new design;

FIG. 2 is a front view of the post assembly for a mobile workstation shown in FIG. 1;

FIG. 3 is a rear view of the post assembly for a mobile workstation shown in FIG. 1;

FIG. 4 is a right side view of the post assembly for a mobile workstation shown in FIG. 1;

FIG. 5 is left side view of the post assembly for a mobile workstation shown in FIG. 1;

FIG. 6 is a top view the post assembly for a mobile workstation shown in FIG. 1; and,

FIG. 7 is a bottom view of the post assembly for a mobile workstation shown in FIG. 1.

The broken lines shown in the figures represent a portion of the mobile workstation and form no portion of the claimed design.

1 Claim, 7 Drawing Sheets
